Patented Mar. 12, 1968

210,505

CUTICLE CLIPPER

Norbert Leopoldi, 4180 Marine Drive,
Chicago, Ill. 60613

Filed Dec. 1, 1966, Ser. No. 4,887

Term of patent 3½ years

(Cl. D86—10)

Fig. 1.

Fig. 2.

Fig. 3.

Fig. 4.

FIG. 1 is a perspective of the cuticle clipper of the present invention particularly showing the construction and arrangement of the cutting surfaces;

FIG. 2 is a top plan view of the cuticle clipper of FIG. 1, particularly illustrating the profile of the cutting head;

FIG. 3 is a side elevation of one side of the cuticle clipper of FIG. 1 illustrating the actuating lever in a raised position; and

FIG. 4 is a side elevation similar to FIG. 3 from the other side.

I claim:

The ornamental design for a cuticle clipper, substantially as shown.
